UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

NEEDLE MOTION FOR AXMINSTER LOOMS.

Application filed September 17, 1928. Serial No. 306,449.

This invention relates to improvements for needle motions for Axminster looms and it is the general object of the invention to compensate for the stretching of the cable customarily employed in imparting the weft laying and withdrawing movements to the needle.

Axminster looms which weave relatively wide fabrics customarily employ a weft laying needle which is movable along a rail by means of a flexible cable such as a cotton rope, this rope being wound around a drum and being connected to the carriage for the needle which slides along the rail. It is found that as the loom continues to operate the rope will stretch so that although the reciprocating movements of the drum may be correct yet the needle itself will have greater movements than are desired because of the slackness of the rope. This stretching is particularly objectionable when wide Axminster looms are run at comparatively high rates of speed because of the fact that the needle cannot be made to register with the selavage shuttle on that side of the loom opposite the needle motion.

In co-pending application Ser. No. 43,604 filed July 14, 1925, by Robertson there is shown a slack taking-up device on the outer end of the needle rail and this device has worked satisfactorily, permitting a considerable increase in the rate at which the loom is run and operating to hold the needle in proper position so that it may register with the selavage shuttle. The device of the aforesaid application, however, acts on the strand of rope extending from one side only of the needle carrier and it is an important object of my present invention to provide means for keeping both strands of rope taut. It is found under certain conditions that if the sheave near the fabric is held stationary all of the compensating for the stretch of the rope takes place in one direction so that the carriage for the needle moves outwardly a slight amount after each taking-up movement of the segment and pawl shown in said application. By the device set forth herein the cable is moved in opposite directions so that no matter what the slack taking-up movements to absorb the stretch of the cable are, the needle carrier and

therefore the needle will be in proper position.

It is a further object of my present invention to provide a pair of movable sheaves for the actuating cable of an Axminster needle which shall be operatively connected to move together but in opposite directions and under influence of a single weighted member.

It occasionally happens that the two strands extending from the drum to the needle carrier are of unequal lengths so that the stretching to which they are subject will be unequal and it is a further object of my invention to provide means for acting on each strand so that the amount of slack taken up may be proportioned to the amount occurring, thereby keeping both strands under proper tension and the needle carrier in correct position.

With these and other objects in view which will appear as the description proceeds, my invention resides in the combination and arrangement of parts hereinafter described and set forth in the claims.

In the accompanying drawings wherein one form of my invention is shown,

Fig. 1 shows the right hand end of a wide Axminster loom needle motion, parts being removed to permit the device to be shown more clearly,

Fig. 2 is a detail top plan view taken in the direction of arrow 2, Fig. 1, and

Fig. 3 is a detail elevation looking in the direction of the arrow 3 in Fig. 1.

Referring to the drawings, the loom frame 10 has secured thereto a needle motion frame 11 on which is pivotally mounted a gear segment 12 oscillating about a center 13 by reason of a link 14 connected to a rotating arm 15. Said segment meshes with a pinion 16 mounted on shaft 17 held in bearing 18. A cable drum 19 is secured to the shaft 17 and has wrapped therearound two strands 20 of cable, the needle inserting strand 20 extending to the left as shown in Fig. 1 and the needle withdrawing strand 21 extending to the left as shown in Fig. 1 and the needle withdrawing strand 21 extending to the right. A needle carrier 22 is slidable along the needle rail 23 and has secured thereto the needle 24 the left hand end of which as shown in Fig. 1 has an eye 25 for the weft

W. One end of each of the cables is connected to the carrier.

As shown in section in Fig. 1 and in plan in Fig. 2 a selvage shuttle S moves in an 5 arcuate groove 26 formed in a stationary frame 27 bolted as at 28 to a fixed part of the frame of the loom, such as a stand 29. A rocking shaft 30 extending through stand 29 has keyed thereto as at 31 an arm 32 having engagement with shuttle S to move the same back and forth in the arcuate groove 26. The matter thus far described is of 10 very common construction in wide Axminster looms and forms no part of my present 15 invention.

The needle rail 23 has projecting upwardly from the right hand end thereof as shown in Fig. 1 a horn 33 to which is pivotally connected as at 34 a lever 35 having a horizontal arm to which is attached a weight 36. Said lever 35 has a depending arm 37 provided with a pin 38 which affords pivotal support for sheave 39 around which the strand 21 is trained. The lever 35 is also 20 provided with an integral ratchet segment 40 which cooperates with a pawl 41, the effect of said pawl being to prevent retrograde movement of the lever in a left hand direction as viewed in Fig. 1. The matter 25 supported by the horn 33 is substantially the same as shown in the aforesaid co-pending application filed by Robertson and forms no 30 part of my present invention.

As previously pointed out a construction 35 of the form already described herein affords satisfactory means for permitting increased speed of the needle motion, but under certain conditions it is found necessary to move the needle relatively to the needle carriage 40 22. In order to obviate this necessity I provide a second horn 50 on the needle rail and pivot thereto as at 51 a substantially vertical lever 52 to the lower end of which is pivoted as at 53 a sheave 54 around which the needle 45 inserting strand 20 is trained. Said lever 52 has an upwardly projecting arm 55 to which is connected the left hand end of a connector rod 56. The right hand end of 50 said connector rod is attached to the arm 37 by a stud 57 adjustable toward and from the center of lever 35 in slot 58.

In operation, as the strands of the cables 55 stretch they permit the weight 36 to move the sheave 39 to the right as viewed in Fig. 1. When this takes place the rod 56 will be placed under tension to cause a movement of lever 52 in a clockwise direction around the center 51 to move the sheave 54 to the 60 left so that the sheaves move in opposite directions. Each strand therefore has its slack taken up and for this reason the position of the needle carrier remains practically unchanged and is always in proper position 65 relatively to the position of the oscillating geared segment 12.

The slot 58 permits adjustment of the relative movements of the sheaves so that if under certain constructions of looms the inserting strand 20 is shorter than the withdrawing strand 21 so as to be subject to less 70 stretching because of use and changing atmospheric conditions the amount of movement of the sheave 54 may be lessened as compared to the movements of the sheave 39. In this way the needle carriage may be 75 kept in its proper position even though the withdrawing strand of the cable be of different length than the needle inserting strand.

By referring to Fig. 1 it will be seen that 80 the sections of cable are positively connected to the drum, each section being held under a clip 60 held to the drum by a bolt 61. A knot 62 in each section causes the drum to exert a positive pull on the sections. 85

From the foregoing it will be seen that I have provided a needle motion for an Axminster loom wherein both the needle inserting and withdrawing strands may be kept taut by devices which change the range 90 of movement of each strand as they stretch, to the end that the needle carrier will be properly located and thus render unnecessary any attending changes in the needle. It will further be seen that the device may 95 be so constructed that the simultaneous movements of the sheaves may not necessarily be equal in extent but may be proportional to the amount of stretching to which the corresponding strand is subject. 100

Having thus described my invention it will be seen that changes and modifications may be made therein by those skilled in the art without departing from the spirit and scope of the invention and I do not wish to 105 be limited to the details herein disclosed, but what I claim is:

1. In a needle motion for an Axminster loom, a needle rail, a needle carrier, an oscillating drum, a pair of flexible elements one 110 end of each of which is connected to the drum, the other ends of said elements being connected to the needle carrier which reciprocates along the needle rail, a sheave for each element, and means to cause said sheaves to move in opposite directions when said elements become slack, whereby the needle carrier will maintain the same position relatively to the rail for all adjusted 115 positions of the sheaves. 120

2. In a needle motion for an Axminster loom, a needle rail, a needle carrier movable therealong, an oscillating drum, a pair of flexible needle actuating elements one end of each of which is connected to the drum, the other ends of said elements being connected to the needle carrier, a sheave for each element, a movable mounting for each sheave, a connection between said mountings to cause the same to move in unison but in opposite di- 125 130

rections, and means operative upon the occurrence of slackness in the elements to cause said mountings to move in opposite directions to take up slack in each element to maintain the same relative position between the carrier and the rail.

3. In a needle motion for an Axminster loom, a needle rail, a needle carrier movable therealong, an oscillating drum, a pair of 10 needle actuating cables one end of each of which is connected to the drum, the other ends of said cables being connected to the needle carrier, a sheave for each cable, a lever for each sheave and on which the latter is rotatably mounted, means to connect 15 said levers together to cause the same to have simultaneous movements in opposite directions, and a weighted device operatively connected to one of said levers and effective 20 upon the occurrence of slackness in the cables to move both levers through the means to take up slack in each cable and maintain the same relative position between the rail and the carrier.

25 4. In a needle motion for an Axminster loom, a needle carrier, an oscillating drum, a pair of cables one end of each of which is connected to the drum, the other ends of said cables being connected to the needle 30 carrier, a sheave for each cable, a selvage shuttle to cooperate with the needle, a movable mounting for each sheave, and means to cause said mountings to have simultaneous 35 movements in opposite directions upon the occurrence of slackness in the cables, whereby said needle may be maintained in proper position relatively to the selvage shuttle.

5. In a needle motion for an Axminster loom, a needle rail, a needle carrier movable 40 therealong, an oscillating drum, a pair of cables one end of each of which is connected to the drum, the other ends of said cables being connected to the needle carrier, a sheave for each strand, a lever for each 45 sheave pivotally mounted with respect to the needle rail, means to cause simultaneous movements in opposite directions of said levers when slackness occurs in the cables, and a device associated with one lever to prevent 50 retrograde movement of both levers, whereby said levers retain their different settings.

6. In a needle motion for an Axminster

loom, a needle rail, a needle carrier movable therealong, an oscillating drum, two cables one end of each of which is connected to the drum, the other ends of said cables being connected to the needle carrier, a pair of 55 sheaves movable simultaneously in opposite directions, one sheave for each cable, and means to cause said simultaneous opposite movements of the sheaves upon the occurrence of slackness in the cables, to the end that the same relative position may be maintained between the needle and the rail for all 60 lengths of the cables.

7. In a needle motion for an Axminster loom, a needle rail, a needle carrier movable therealong, an oscillating drum, a pair of cables, one end of each of which is connected to the drum, the other ends of said cables 70 being connected to a needle carrier, a sheave for each strand, a lever for each sheave pivoted with respect to the needle rail, a connecting means to attach the levers together to cause the same to have simultaneous opposite movements, means to cause said simultaneous 75 opposite movements when slackness occurs in the cables, and an adjustable connection between said connection and one of the levers, whereby the movements of the sheaves in taking up slack may be made proportional to the lengths of the cables.

8. In a needle motion for an Axminster loom, a needle rail, a needle carrier movable along the rail, an oscillating drum, a pair of 85 cables one end of each of which is positively connected to the drum, the other ends of said cables being connected to the needle carrier, a sheave for each strand, a lever for each sheave pivotally mounted with respect to the 90 needle rail, a rod connecting said levers to have simultaneous opposite movements, and adjustable connections between one end of said rod and one of the levers to vary the position of the point of attachment of said rod to said lever relatively to the fulcrum of the latter, whereby the amounts of movement of the sheaves to take up slack in the cables 95 may be made proportional to the lengths of the cables.

In testimony whereof I have hereunto affixed my signature.

WALTER H. WAKEFIELD.
